HEADSET

Clayton D. Mullin, St. Paul, Minn., assignor to
 Telex Inc., St. Paul, Minn., a corporation of
 Minnesota

Application September 15, 1945, Serial No. 616,609

12 Claims. (Cl. 179—156)

1 This invention relates to head sets and more particularly to sound reproducer head sets of the type that may conveniently be used for communicating sound waves through the head set directly to the user's ears.

It is an object of the invention to provide an improved head set which may be used in place of ordinary mechanical apparatus for dictaphones, physicians' stethoscopic apparatus, diagnostic apparatus and for telegraph and telephone operators where it is desired that the message be communicated to the operator's ears without producing sound waves generally in the space where the operator is utilizing the device. It is a further object of the invention to provide a neat, light-weight head set utilizing a midget receiver of the type customarily used in hearing aid devices. It is a further object of the invention to provide an improved light-weight head set of plastic construction and formed so that it may be adjusted to various head widths. It is also an object of the invention to provide a head set wherein the sound reproducer apparatus is contained as a part of the hinge joint of the head set.

Other and further objects of the invention are those inherent in the apparatus herein illustrated, described and claimed.

The invention is illustrated in the drawings wherein

Figure 1 is a top plan view, partly in section, of the complete head set;

Figure 2 is a front elevational view of the complete head set adjusted to its narrowest position;

Figure 3 is a side elevational view of the head set shown in Figures 1 and 2;

Figure 4 is a fragmentary sectional view of an alternative ear tip construction;

Figure 5 is an enlarged fragmentary view of a portion of the hinge joint;

Figure 6 is a plan view of one portion of the hinge joint in the direction of arrow 6—6 of Figure 7;

Figure 7 is a fragmentary sectional view of the portion of the hinge joint shown in Figure 6 taken along the line 7—7 of Figure 6;

Figure 8 is a fragmentary sectional view of the portion of hinge joint shown in Figures 6 and 7 taken along the lines 8—8 of Figure 6;

Figure 9 is a top elevational view, partly in section, of the other part of the hinge joint, the sectional portion being taken along the lines 9—9 of Figure 10;

Figure 10 is a front elevational view, partly in

2 section, of the portion of the hinge shown in Figure 9. The sectioned part of Figure 10 is taken along the lines 10—10 of Figure 9;

Figure 11 is a sectional view of the assembled hinge joint taken along the lines 11—11 of Figure 5;

Figure 12 is a fragmentary sectional view taken in the direction of arrows 12—13 of Figure 14 and showing the hinge joint in the position of Figure 2, i. e. with the head set adjusted so as to bring the ear tips closest together;

Figure 13 is a sectional view corresponding to Figure 12 taken along the lines 12—13 of Figure 14, but showing the hinge rotated so as to move the ear tips to their limiting open condition;

Figure 14 is a sectional view taken along the lines 14—14 of Figure 13; and

Figure 15 is a top view of the plate 50.

Throughout the drawings corresponding numerals refer to the same parts.

Referring to the drawings, the assembled head set comprises a hinge joint generally designated 20 having two hinge parts generally designated 21 and 22 to which there are attached a pair of tubular members 23 and 24 that are curved as shown in Figures 1, 2 and 3 and inturned at their upper ends. On the inturned upper ends of the tubular members 23 and 24 there are tubular ear tips 25 and 26 which may be shaped as shown in Figures 1-3 or as shown at 27 in Figure 4 wherein the ear tip has a somewhat flanged shape at 28 and is provided with one or more non-concentric sound conducting orifices 29.

The hinge 20 is constructed so as not only to serve as the hinge joint but also to contain the sound reproducer element. Hinge 20 is composed of two main elements 21 and 22. One of the elements 21 is best shown in Figures 9 and 10, and consists of a cup-shaped recess 30 which is generally of cylindrical shape and has a closed bottom 31 and a flange at 32 terminating in a threaded opening at 33. The cylindrical member 30 has an upwardly extending side wall 35 around a part of its periphery as shown in Figure 10, where the side wall 35 terminates at 36 and 37. The side wall 35 has attached to it a tubular side arm 38 which extends in a plane which is substantially perpendicular to the axis

of the cylindrical cup 30. The tubular side arm 38 is tapered on the outside and is provided with a socket 39 which receives the tube 23, the latter being cemented or otherwise fastened in place. The member 23 extends to a point near the bottom internal flange 40 which is apertured at 41

and communicates with an arcuate channel 42 for a purpose hereinafter described.

The cylindrical recess 30 is of a shape so as neatly to receive an electromagnetic sound reproducer or "receiver," which is preferably of the type ordinarily used in hearing aid sets. Such receivers are of very small size, being less than $\frac{3}{4}$ inch in diameter and less than $\frac{3}{8}$ inch thick. The receiver which is shown at 44 in Figures 11 and 14 has a cylindrical body and is provided with a flange at 45 which seats in the recess 32. The diaphragm of the receiver is slightly below the level 46 which is the upper edge of the flange 45. The diaphragm 48 is indicated in section in Figure 11. The receiver is held in place by a plate generally designated 50 which is threaded on the edge so as to screw into the threads 33 of the hinge member. The plate 50 is turned out at its center part 51 over the diaphragm and the edge is provided with two or more apertures 52 by means of which a spanner wrench may be inserted and the plate screwed firmly into place. It is to be understood that the plate is of a thickness so as to bear down upon the upper edge 46 of the receiver flange 45 and that there is accordingly a slight clearance space below the plate to the diaphragm 48, thereby permitting sound waves to emanate completely in all directions between the plate 50 and the diaphragm. The apertures 52—52 serve not only as wrench sockets but also permit the sound waves emanating from the diaphragm to pass upwardly in the direction of arrows 54 into channel 67 through which the sound is conducted to the tubes 23 and 24 and to ear tips 25 and 26 as hereinafter explained. At the center of the plate there is an integral upstanding hinge pin 56 which is internally threaded at 57 to receive the hinge retaining screw 58, the latter being seated upon a spring washer 59.

The spring washer 59 holds in place the second main half of the hinge structure, this being shown best in Figures 6, 7 and 8. This portion of the hinge has a cover part 63 which has a recess 64 in its outer side to receive the screw 58 and spring washer 59 as shown in Figures 11 and 14. The central aperture 65 of the cover 63 is of a size to fit neatly upon the hinge pin portion 56, and the surface 66 fits directly upon the upper surface of the cover plate 50. Concentrically around the aperture 65 there is an annular opening or groove 67 which is provided with two radial apertures 68 and 69 as shown in Figure 6. The aperture 69 communicates through the wall portion 70 and to a tubular extending arm 71 which, like arm 38 of the cooperating hinge portion, serves to receive the ear tube as shown in Figures 2 and 6. The diameter of the annular recess 67 is such that it overlies the two apertures 52—52 in the retaining plate 50. Hence, any sound from the diaphragm 48 which passes through the apertures 52—52 enters the annular recess 67 and thence part of it passes out through the opening 69 into the tubular arm 71 and thence into the tubular extension 24. The aperture 68, Figure 6, is located so that it will always be within the range of movement of the arcuate slot 42 of the opposite hinge piece, Figures 5, 10, 12 and 13. Thus, it will be seen that when the hinge is moved from the position shown in Figure 12 to the position shown in Figure 13, the arcuate channel 42 always overlies the opening 69. Hence, regardless of whether the hinge is moved to the position shown in Figure 12 in which position the

ear tips are closest together or is moved to the position shown in Figure 13 in which the ear tips are farthest apart. Aperture 68 is always in communication with slot 42. Thus, sound waves in the annular channel 67 are freely permitted to pass through the opening 68 and thence through the arcuate channel 42, channel 41 and into the tubular arm 38 and thence to the tubular extension 23.

10 The limits of the hinging motion are determined by the arcuate length of the side wall 70 of the hinge member shown in Figure 6 and the arcuate length of the side wall 35 of the hinge member shown in Figure 10. Thus, when part 15 73 of wall 70 is brought into engagement with the part 37 of wall 35, the hinge is stopped at its most narrow condition. Likewise, when the portion 74 is brought into engagement with the portion 36, the hinging motion is stopped at the 20 widest position of movement. In every condition, however, sound may pass freely from the diaphragm, thence through opening 52 into the annular channel 67 and thence out through the openings 68 and 69 and thence into the tubular arms 38 and 71, respectively, and through the tubular extensions 23 and 24 to the ear tips 25 and 26.

25 The spring washer 59 is of a shape such as to apply just sufficient tension to hold the hinge joint snugly against accidental displacement. 30 The washer is preferably dished slightly and may, if desired, have radial cuts inward around its periphery to increase its resilience. The hinge can be moved freely to any position so as to 35 facilitate adjustment by the operator, and in any position the adjustment is held by friction due to the spring pressure of washer 59.

35 The receiver 44 is provided with a connector block 75 which terminates in the cord 76. The connector block is inserted through an opening 77 in the side wall of the cylindrical chamber 30 in the hinge member.

40 While metals may be used in constructing the head set, it is preferred to make the entire apparatus of molded plastic. Thus, the two hinge members 21 and 22 may easily and conveniently be produced from molding plastic such as the phenolic resins, urea formaldehyde resins, the vinyl resins, methyl methacrylate resins and any other suitable types of molding resins. Likewise 45 the tubular extension 23 and 24 and the ear tips 25 and 26 may be made of plastic. In this way an artistic as well as light-weight device can 50 easily be produced and the entire weight of the apparatus reduced so that the operator is hardly 55 aware that the device is in place during operation.

55 The length and shape of the tubular extension 23 and 24 is such as to bring the hinge 20 in a position slightly below the operator's chin when 60 the device is worn in service.

65 As many apparently widely different embodiments of this invention may be made without departing from the spirit and scope thereof, it is to be understood that I do not limit myself to the specific embodiments herein except as defined by the appended claims.

What I claim is:

70 1. A head set comprising a two part hinge, one of said parts having a recess portion with an open face and an integrally formed tubular arm extending outwardly therefrom, said recess portion being adapted to receive a telephone receiver of the hearing aid type, a second matching hinge part having a cover portion fitted to overlay said 75 open face of the recess portion and an integrally

formed tubular arm extending outwardly therefrom, said tubular arms being approximately in the same plane, a hinge pivot means connecting the recess portion at its open face and the cover portion, said cover portion, hinge pivot means and recess portion being apertured so as to provide an uninterrupted sound passageway from the recess to each of the tubular arms, a pair of tubes mounted as tubular extensions of the tubular arms, said tubes being shaped to extend around a user's face and extend into the user's ears, and a telephone receiver of the hearing aid type mounted in the recess whereby sound waves from said telephone receiver pass through said uninterrupted sound passageway.

2. A head set of the type set forth in claim 1 further characterized in that the hinge pivot means includes a plate detachably secured so as to fill the open face of said recess, said plate being provided with an extending pivot which passes through and is attached to the cover portion of the matching hinge part.

3. A head set comprising a hearing aid type receiver of cylindrical shape, a hinge having a tubular arm terminating in a cup shaped recess shaped to contain said receiver, a plate detachably secured to cover said cup shaped recess for retaining the receiver therein, said plate being provided with a hinge pin extending outwardly therefrom, a cover for said plate pivotally secured to the hinge pin, said cover having a tubular arm extending therefrom, said plate and cover being apertured so as to form a sound conducting channel from the receiver to a hole in each tubular arm, a tubular extension attached to each tubular arm, said extensions being curved towards each other and abruptly inturned and fitted with ear tips for engagement in the wearer's ears.

4. The apparatus of claim 3 further characterized in that the arms are shaped so as to allow limited angular movement with respect to each other around said hinge pin as an axis.

5. The apparatus of claim 3 further characterized in that the apertures in the plate fit in spaced relation to the receiver when in place on the cup-shaped recess and is apertured so as to allow sound waves from the receiver to pass through said plate and the cover has a cooperating annular channel apertured radially to communicate with said tubular arms.

6. A head set comprising a two-part hinge, a first hinge part having a recess portion adapted to receive a telephone receiver of the hearing aid type, a cover plate for said recess portion, the cover plate having means for retaining the receiver in the recess portion, said cover plate being undercut centrally so as to provide a clearance space over the diaphragm of said receiver, apertures through said cover plate communicating with the clearance space, a hinge pivot extending upwardly from the upper face of the cover plate, a second hinge part having a cover portion adapted to cover said recess portion and said cover plate, said second hinge part having an opening therein surrounding said hinge pivot, fastening means for retaining said second hinge part on said hinge pivot, a lateral aperture in each of said hinge parts communicating with the space above the cover plate, a tubular extension extending from each of said lateral apertures, said extensions being shaped to extend around a user's face and into a user's ears.

7. A head set comprising a two-part hinge, a first hinge part having a generally cylindrical

recess therein, a telephone receiver of the hearing aid type in said recess, said first hinge part having a shoulder on the internal wall adapted to support the upper edge of said telephone receiver, a cover plate for said recess, said cover plate bearing on the upper edge of said telephone receiver rigidly to retain the receiver on said shoulder, said cover plate being undercut centrally so as not to contact said receiver except at the periphery thereof and to provide a clearance space above said receiver, apertures in said cover plate communicating with said clearance space, a generally cylindrical hinge pivot extending upwardly from the top of the cover plate, a second hinge part adapted to overlie the first hinge part and said cover plate, said second hinge part having an aperture surrounding said hinge pivot, fastening means for retaining said second hinge part on said hinge pivot, an annular recess in the lower face of the second hinge part, said annular recess overlying the apertures in the cover plate and communicating therewith, a pair of lateral recesses communicating with the annular recess and extending through the sides of the second hinge part, one of said lateral recesses communicating with an ear tube extending from said second hinge part, the first hinge part having an upstanding portion having an arcuate face, and lying adjacent a portion of the second hinge part, said arcuate face having an arcuate recess therealong and an aperture communicating with said arcuate recess and with a second ear tube, said arcuate recess communicating with the other of said lateral recesses, said two hinge parts being pivotable about said hinge pivot, and stop means on said hinge parts to limit the pivotal movement such that said other lateral recess is contantly in communication with said arcuate recess.

8. A head set comprising a hinge having two portions each having a tubular side protuberance and an integral overlap hinge part, the latter being reduced in thickness to approximately one-half the thickness of the side protuberance so that when the integral overlap hinge parts are placed in overlapping relation, the total thickness of the hinge so formed is not substantially more than the thickness of the side protuberances, said side protuberances being in approximately the same plane, a hinge pin extending through the hinge parts so as to hold them together for limited hinge motion, one of said hinge portions being formed with a protuberance forming an antrum, a receiver mounted within said antrum in and substantially concentric therewith and tubes extending from each of said tubular side protuberances and terminating in ear tips, the hinge parts being channeled for conveying sound waves from the antrum in which the receiver is mounted and thence through both tubular side protuberances and thence through the tubes to the ear tips.

9. A head set of the character set forth in claim 8 wherein the hinge is of molded plastic.

10. A very light weight head set comprising a hinge having two tubular protuberances connected with extending tubes that terminate in ear tips, said tubular protuberances being in the same plane and hinged by each having an integral hinge part offset sufficiently so that when the segments of the two hinge parts are brought into overlapping relation their combined thickness is not substantially more than the thickness of the protuberances, one of said hinge parts having an integrally formed small antrum extending slightly beyond the combined thickness of said hinge parts, a hinge pin connecting the hinge

parts and a sound reproducer of the hearing aid type having a diameter not substantially exceeding that of the overlapped integral hinge parts mounted in said antrum concentrically therewith, said hinge parts being channeled so as to provide sound passages extending from the sound reproducer through the tubular protuberances and extending tubes to the ear tips.

11. As an article of manufacture, a very light weight head set comprising two molded plastic parts shaped to form a hinge, one of said parts having a small antrum concentric with the hinging axis, said antrum terminating as a circular opening concentric with said axis of hinging, said part also having a tubular side arm extending sideways from said antrum partly below and partly above the plane of said circular opening, a tiny sound reproducer of the hearing aid type seated in said antrum with the sound diaphragm thereof directed towards said opening, a hold-down plate fastened into said opening above the diaphragm so as to hold the sound reproducer in place, said plate having a central pivot and holes through said plate offset from the pivot, the other hinge part having a disk-like portion overlying the plate and having an opening through which said pivot extends, means for fastening said disk portion to the pivot, and a side arm likewise extending from said disk-like portion at a level such that when the parts are assembled the side arms of both hinge portions will be in substan-

tially the same plane, the hinge parts being formed with integral stops for limiting the hinging motion of said parts, said parts being provided with channels extending from the hold-down plate through each side arm, and tubes terminating in ear tips extending from each side arm.

12. The device described in claim 11 further characterized in that said channels are formed to include a circular groove in that part of the disk-like portion which overlies the plate, said circular groove overlying the holes through said plate, said groove having radial connections extending to each side arm when the parts are assembled.
